POWER TRANSMITTING MECHANISM

Berthold Freund, Berlin-Schoneberg, Germany,
assignor to Internationale Tobis Maatschappij
N. V., Amsterdam, Netherlands

Original application August 10, 1929, Serial No.
385,000. Divided and this application Decem-
ber 8, 1931, Serial No. 579,756. In Germany
August 20, 1928

7 Claims. (Cl. 271—2.3)

My invention relates to power-transmitting mechanisms.

It is an object of my invention to so design a mechanism of this type that it will translate unequal rotation of a driving member into substantially uniform rotation of a driven member.

To this end, in combination with a driving member which is rotatable at unequal velocity, such as a manually operated crank for driving a sound and/or picture recording apparatus, I provide an energy accumulator, such as a spiral spring which is connected to the driving member at one end and to a driven member at the other end, a centrifugal governor for equalizing the velocity of the driven member, and means adapted to be controlled by the spiral spring or other energy accumulator, for regulating the centrifugal governor.

For instance, if the energy accumulator is a spiral spring, the regulating means may be designed as follows: A pair of arms engages opposite sides of the spiral spring under resilient pressure and are operatively connected to a check for restraining the centrifugal weights of the governor. As the diameter of the spiral spring intermediate the points where it is engaged by the arms varies with the load which is brought to bear on the spring by the rotatable member, the check is displaced in conformity with the variation of the diameter and regulates the centrifugal governor by restraining its weights.

In more general terms, it may be said that a dimension of the energy accumulator is varied by the varying load on the energy accumulator, and that the means for regulating the centrifugal governor is controlled in conformity with the variation of such dimension.

The lack of uniformity in the rotation of the driving member is made up for by the accumulator so that the driven member rotates at uniform, or substantially uniform, velocity under the control of its centrifugal governor.

My invention is particularly suitable for apparatus operated by human power for making sound and picture records, as described in my co-pending application for patent of the United States, Ser. No. 385,000, filed Aug. 10, 1929, for "Method of and apparatus for making sound records" in which the apparatus are operated by the usual cranks. This application is a division of the above application, Serial No. 385,000, which has matured into Patent No. 1,974,709, September 25, 1934.

55 Uniform, or substantially uniform, rotation of

the driven member cannot be obtained by the existing power accumulators or buffers in the shape of fly wheels, springs and the like, as these merely absorb shocks and vibration but do not influence the speed of the driven member; nor by centrifugal governors which limit the speed without maintaining it uniform.

My invention possesses a wide range of usefulness in that it can be adapted to any power transmission in which variations in the driving torque and/or speed must be equalized.

In the accompanying drawing, several mechanisms embodying my invention are illustrated more or less diagrammatically by way of example.

15 In the drawing

Fig. 1 is a diagram of an apparatus in which the energy accumulator is a spiral spring and the centrifugal governor is regulated in conformity with the variation of the spring diameter.

20 Fig. 2 is a partly sectional elevation of a mechanism in which the reaction, and not the size, of a spiral spring is utilized for regulating the governor.

25 Fig. 3 is a sectional elevation of a mechanism in which the difference of the speeds of the driving member and the energy accumulator are employed for regulating the governor.

Fig. 4 shows an optical, and

30 Fig. 5 a combined optical and acoustic indicator for the apparatus in Fig. 3.

Referring now to the drawing, and first to Fig. 1, 140 is a crank on a shaft, 139 is a pawl in combination with a ratchet wheel for preventing rotation of the crank shaft in the wrong direction, 143 is a spur gear which is free to turn with respect to the shaft, and 141 is a spiral spring or energy accumulator which is secured to the crank shaft at one end and to the spur gear 143 at its other end 142. 144 is a pinion in mesh with the spur gear 142. 150 and 145 are bevel gearings in combination with a vertical shaft 151 and a horizontal shaft 152, and 148 is a mechanism operatively connected to the shaft 152 for feeding a sound record 149. As mentioned, I am not limited to the particular case of records but may operate any member from the shaft 152. 146 is a bevel gearing on the shaft 152 and on the shaft of a centrifugal governor 147, and 160 is a hollow check surrounding the governor for limiting the radial movement of its fly weights. The check 160 is attached to the lower end of a rod the upper end of which is pivoted to two links 158 and 159 at 157. The upper ends of the links are pivoted to a 35

pair of double-armed levers 153 and 162 at 155 and 156, respectively, which are pivoted at 161 and with their free ends engage the energy-accumulator spring 141. 154 is a spring which holds the free ends engaged with the energy-accumulator spring.

As the load on the spring 141 is varied by the varying torque exerted on it the arms of the levers 153, 162 are moved more or less apart and 10 the check 160 is raised or lowered. By these means the speed of the driven shaft 152 is maintained constant independently of the torque and the tension it exerts on the spring 141. The inner face of the check 160 must obviously be 15 shaped in conformity with the desired regulation.

Fly wheels or any other appliances for maintaining constant the speed of a shaft, might be provided instead of the means described.

20 Any other energy-accumulating means than the spring 141 may be provided, for instance, pneumatic means, weights, etc., and other means than a centrifugal governor might be connected to the shaft 152.

25 Referring now to Fig. 2, this shows a mechanism in which the reaction of the energy accumulator, here shown as a spiral spring 171, and not its diameter, is utilized for influencing the position of the check 160 with respect to governor 147. 180 is a shaft to the rear end of which the inner end of the spring 171 is attached while 30 its outer end is attached to a pin 190 on a spur gear 191. The spur gear meshes with a pinion 192 on the shaft of the governor 147. 163 is a spur gear on the governor shaft which meshes with a pinion 193 on the shaft 152.

185 is a spur gear fixed on the outer end of a shaft 164 on which is fixed a threaded spindle 181, 170 is a crank on the spur gear, 186 is a 40 pawl for preventing rotation of the spur gear in the wrong direction and 173 is a rearward extension of the crank, with a fork 174 at its free end. Seated on the spindle 181 and engaging in its thread is a hollow boss 182 from which extends a lever 178 in the shape of the letter L, and to the rear end of which the spring shaft 180 is attached. 175 is a radial arm on a ring which is mounted to turn on the boss 182 and is engaged by the fork 174, 172 is a spring connecting the 45 end 176 of the arm to the end of lever 178, and 177 is a gear on the boss 182, with a pawl 179.

50 The arm 175 is deflected from its radial position more or less in conformity with the tension of the spring 171 under the varying torque, and the spring 172 is stretched in proportion. The arm 178 is under the reaction of spring 171, and the relative angular displacement of the arms 178 and 175 which is translated into relative rotation of the spindle 181 and the boss 182, causes 55 the spindle 181 to shift axially which movement is translated into axial displacement of check 160 by a rod 183 on a slide 184. This rod with its upper end engages in a groove of the spindle 181 and its slide 184 is, by a cable on a sheave 165, 60 connected to a slide 166 to which the check 160 is secured, and a pull-back spring 154 is attached to the rear end of the slide 165.

65 Referring now to Fig. 3, 200 is the shaft of a crank 195, 197 is a pinion on the shaft, and 161 70 it a ratchet wheel at the rear end of the shaft the pawl 139 of which is fulcrumed on a spring casing 196. The casing contains an energy accumulator such as the spiral spring 171, Fig. 2, whose outer end is secured to the inside of the 75 spring casing, and whose inner end is secured to

a pinion 205. The pinion is free to rotate about the shaft of the spring casing 196, except for the connection of the two members by the spring in the casing. The pawl 139, like the same pawl in Fig. 1, prevents rotation in the wrong direction, as the spring casing is entrained only if the shaft 200 is turned against the pawl. 209 is a shaft on which are mounted the two planet wheels 199, 208 meshing with a sun wheel 210, and 198 is a spur gear on shaft 209 which meshes with 10 pinion 197. 207 is another spur gear on the shaft 209 and 206 is an intermediate pinion, meshing with the pinion 205 which, as mentioned, is free to rotate on the shaft of the spring casing 196. The spur gears 198 and 207 are rigidly connected to the adjacent planet gears 199 and 208. The planet wheels, consequently, are rotated in opposite directions by the crank 195 and the spring casing 196, at 20 equal ratio. The sun wheel 210 is free to turn about the shaft 209 and its shaft 211 is connected to a bracket 212 which is mounted to rock about shaft 209 and at its upper end has a fork 167 by which it engages a bell-crank 215, 216, 217 for shifting the check 160. Rotation is imparted to 25 the shaft 152 through gearing 202, 203 from a spur gear rim on the spring casing 196.

213 is an indicator at the lower end of bracket 212 opposite the fork 167, and 214, Fig. 4, is a dial on which the position of bracket 212 is indicated. The central mark 169 on the scale corresponds to the medium tension of the spring in the casing 196, and 168, 170 are points corresponding to the maximum and minimum tension of the spring. The load may vary between these 30 limits without interfering with the uniformity of rotational speed at 148.

35 Referring to Fig. 5, the marks 168 and 170 are replaced by checks 218 and 219, each with a pull-back spring, and hammers 222 and 223, respectively, for striking bells 220 and 221. Instead of checks and bells, electric contacts and lamps may be provided for signalling. Obviously, 40 acoustic signals may also be operated electrically if required.

45 The mechanism for moving records such as sound and picture films which has been generally indicated at 148, may be modified in various ways and combined with any desired clutching or entraining means.

50 I claim:

1. A power transmitting mechanism comprising a driving and a driven member, an energy accumulator, speed-equalizing means connected to said members, and means for indicating the 55 reaction of said accumulator.

2. In a power transmitting mechanism, a driving member rotatable at unequal velocity, a driven member, an energy accumulator connected to said driving and to said driven member, 60 a centrifugal governor connected to said driven member for equalizing its velocity, and means adapted to be controlled by said energy accumulator for regulating said governor.

3. In a power transmitting mechanism, a driving member rotatable at unequal velocity, a driven member, a spring connected to said driven member at one end and to said driving member at the other end, as an energy accumulator, a 65 centrifugal governor for equalizing the velocity of said driven member, and means controlled by the reaction of said spring for regulating said governor.

4. In a power transmitting mechanism, a driving member rotatable at unequal velocity, a driven 75

member, a spring connected to said driving member at one end and to said driven member at the other end, as an energy accumulator, a centrifugal governor for equalizing the velocity of said driven member, means adapted to be displaced by said driving member in conformity with the reaction of said spring, a threaded spindle adapted to be shifted by such displacement, and means operatively connected to said spindle for regulating said centrifugal governor.

5. In a power transmitting mechanism, a driving member rotatable at unequal velocity, a driven member, a spiral spring connected to said driving member at one end and to said driven member at the other end, as an energy accumulator, a centrifugal governor for equalizing the velocity of said driven member, and means operatively connected to said spring so as to be controlled by the variations in its outside diameter 15 for regulating said centrifugal governor.

6. In a power transmitting mechanism, a driving member rotatable at unequal velocity, a driven member, a spiral spring connected to said

driving member at one end and to said driven member at the other end, as an energy accumulator, a centrifugal governor for equalizing the velocity of said driven member, a pair of arms adapted to engage opposite sides of said spring, resilient means for applying said arms to said spring, and means operatively connected to said arms for regulating said centrifugal governor.

7. In a power transmitting mechanism, a driving member rotatable at unequal velocity, a driven member, an energy accumulator connected to said driving and to said driven member in such manner that a dimension of said accumulator is varied by the varying driving power transmitted to said accumulator from said driving member, a centrifugal governor connected to said driven member for equalizing its velocity, and means operatively connected to said accumulator so as to be controlled thereby in conformity with the variation of said dimension, said last-mentioned means controlling said centrifugal governor.

BERTHOLD FREUND.
